UNITED STATES PATENT OFFICE

169,322

FOOD BASKET

Roy Lydick, Brainerd, Minn.

Application December 8, 1952, Serial No. 22,595

Term of patent 14 years

(Cl. D58—4)

To all whom it may concern:

Be it known that I, Roy Lydick, a citizen of the United States, residing at Brainerd, in the county of Crow Wing and State of Minnesota, have invented a new, original, and ornamental Design for a Food Basket, of which the following is a specification, reference being had to the accompanying drawing, forming part thereof.

The single drawing figure is a perspective view of a food basket, showing my new design.

The dominant features of my design reside in the portions shown by full lines.

I claim:

The ornamental design for a food basket, as shown and described.

ROY LYDICK.
